UNITED STATES PATENT OFFICE.

CHARLES H. PEARSON, OF BROOKLINE, MASSACHUSETTS.

FUSE.

Refile of abandoned application Serial No. 435,737, filed January 7, 1921. This application filed July 17, 1924. Serial No. 726,482.

To all whom it may concern:

Be it known that I, CHARLES H. PEARSON, a citizen of the United States, and resident of Brookline, in the county of Norfolk and 5 State of Massachusetts, have invented an Improvement in Fuses, of which the following description, in connection with the accompanying drawings, is a specification, like reference characters on the drawings representing like parts.

My present invention relates to fuses, and more particularly to mechanical time fuses adapted to be applied to ordnance shells for the purpose of detonating the charge therein 15 after a predetermined length of time following the discharge of the shell from a gun.

In fuses in which the firing pin is arranged to move at approximately right angles to the axis of the fuse, no satisfactory 20 arrangement for preventing premature detonation of the primer and charge of the shell has been devised to the present time.

With a view of obviating the objections noted above and with the primary object of 25 improving and perfecting devices of this character, I have devised the subject matter of my present invention, in which safety devices are associated with the firing pin 30 to prevent exploding the primer and the consequent detonation of the powder charge in the base of the fuse by any action of the firing pin prior to its being released following the shock of firing, when such firing 35 pin is installed approximately at right angles to the axis of the fuse.

In carrying out this object, I provide a swivel protecting element interposed between the striking point of the firing pin 40 and the primer, said protecting element being held in this position of safety by a pin to be dropped out of such holding position on the shock of firing and said element then moved and being held out of its protecting 45 position by the centrifugal force which immediately or quickly follows the shock of firing, leaving the path of the firing pin clear for said firing pin to hit and explode the primer when the operation of the time 50 train, set at a predetermined time, releases the pin which is then, by the spiral spring surrounding it, snapped onto and explodes the primer.

Other objects and novel features of construction and arrangement of parts will ap-

pear as the description of the invention progresses.

In the accompanying drawings, illustrating the preferred embodiment of my invention,

Fig. 1 is an elevation of the complete fuse;

Fig. 2 is a central sectional view through the fuse base, illustrating one modification of my improved invention;

Fig. 3 is a sectional plan view on the line of 3-3 of Fig. 2, looking in the direction of the arrows, showing the firing pin in normal, or operative, position;

Fig. 4 is a view similar to Fig. 3, showing the firing pin in its operated, or discharged position;

Fig. 5 is a central sectional view through the fuse base illustrating another modification of my invention;

Fig. 6 is a sectional plan view on the line 6-6 of Fig. 5, looking in the direction of the arrows, showing the firing pin in normal, or operative position, with the rotatable safety device carrying the primer, interposed in the path of the firing pin; and

Fig. 7 is a sectional plan view similar to Fig. 6, but with the primer carried by a plug in the fuse base and in alinement with the firing pin.

Referring to the drawing, and more particularly to Figs. 1, 2, 3 and 4, 10 designates a fuse base provided with threads 11, by means of which it may be attached to the nose of a shell, and with suitable means for holding and allowing the operation of a setting cap 13 for predetermining the moment of detonation of the charge within the shell. Arranged diametrically of the fuse base and approximately at right angles to the longitudinal axis thereof is a hole 14, the outer end of which is adapted to receive the primer holder 15, while the inner end 16 is reduced in diameter to receive the shank portion 17 of a firing pin 18, the shank being a free sliding fit in said reduced inner end 16. The forward portion 19 of the firing pin is a free sliding fit in the hole 14, and the end of the firing pin is pointed, as shown.

A coil spring 20 located in the hole 14 behind the forward portion 19 of the firing pin, surrounds the shank portion 17 and normally tends to force the firing pin into its operated position, or position in engagement with the primer 21 in the primer holder 15.

Adjacent the rear end of the shank portion 17 is a circumferential groove 22, which, when the firing pin is forced to the rear and into its normal position, lies in the circumference of a hole 23, parallel to the axis of the fuse base. Slidably mounted in the hole 23 is a release pin 24, controlled in its movement by the timing train (not shown) normally mounted on the top of the fuse base 10.

Intersecting the hole 14 at a point between the pointed end of the firing pin in its normal position, and the primer 21 is a flat arcuate shaped chamber 25 in which 15 is pivotally mounted a safety device or arm 26, this arm being held in its normal or safety position as shown in Fig. 3, by a pin 27, this pin being a rather tight fit in the hole 28, and capable of being moved out 20 of position with respect to the arm 26 by the shock of firing. An opening 29 through the top of the fuse base 10 into the chamber 25 provides means whereby the arm 26 may be assembled in position in said chamber. This pin 27 is a safety device supplemental to the arm 26, and prevents accidental displacement of said arm 26.

With the elements constituting this modification of my improved device correctly 30 assembled in position as shown in the figures referred to, the firing pin 18 is forced rearwardly in the hole 14, compressing the spring 20, and when the groove 22 comes into alinement with the hole 23, the release pin 24 drops into place to hold the firing pin 18 in the operative position just described. The arm 26 is now moved into the safety position shown in Fig. 3, by 35 properly manipulating the fuse base 10, or by means of a suitable instrument inserted through the hole 29 and the supplemental safety pin 27 inserted in the hole 28. The primer holder 15, with a primer 21 in position therein, is positioned in the open end of 40 the hole 14, and the device is set ready for action. Assuming that the timing train (not shown) is set to operate the release pin 24 at a predetermined length of time after the discharge of the shell and attached 45 fuse from a gun, and that the fuse, assembled and set as shown in Fig. 3 is fired from a gun, the shock of firing causes the pin 27 to be driven into the hole 28 and out of the path of movement of the arm 26. When the shell to which the fuse is 50 attached takes the rifling of the gun, it is rapidly rotated in the direction indicated by the arrows in Figs. 3 and 4, and when the centrifugal force generated by such rotation is equal to or exceeds a predetermined amount, the arm 26 is rotated on its 55 axis from the position shown in Fig. 3 to the position shown in Fig. 4, thus providing a clear path for the firing pin 18 when released.

After the expiration of the time for which the timing train (not shown) is set, the release pin 24 is operated to free the firing pin 18, and the spring 20, expanding, forces the firing pin into engagement 70 with the primer 21 to explode the same and thus cause the detonation of the charge of the shell.

With the arm 26 interposed between the firing pin 18 and primer 21, premature explosion of said primer by the accidental release, from any cause, of the firing pin 18 is impossible. To ensure absolute safety, the pin 27 is provided to positively hold the arm 26 in position until the fuse is subjected to the shock of firing or an equivalent shock.

Referring now to Figs. 5 and 6, I provide, adjacent the outer end of the hole 14, a circular recess 30, having a centrally located hole in the bottom thereof which acts as a bearing for the circular projection 32 on the bottom surface of a disc 33, this disc having a diameter slightly less than the diameter of the recess 30. The upper surface of the disc 33 is provided with diametrically arranged arcuate members 34, which when the disc 33 is in the set, or normal position, as shown in the figures, prevents any movement of the firing pin 95 across the recess 30. Arranged on the upper surface of the disc 33, and approximately midway between the members 34, as clearly shown in Fig. 6, is a primer holding 100 35 holding the primer 21. It is obvious therefore, that should the disc be rotated in a clockwise direction, as viewed in Fig. 6, through an angle of approximately 90 degrees, the member or members 34 will be moved out of the path of movement of the firing pin and the primer 21 brought into said path of movement. In order to assure that the disc 33 can only rotate through an angle of approximately 110 ninety degrees, I have cut away the periphery of said disc as shown at 36, and have inserted a pin 37 in the bottom face of the recess 30, which engages with one end of the cut away portion 36 when the disc 33 is 115 in set or normal position, and with the other end of said cut away portion when the disc is rotated through an angle of approximately ninety degrees, the length of this cut away portion 36 being proportioned to allow such movement. In order 120 to hold the disc 33 and parts carried thereby in the set or normal position, I provide the disc with a hole in alinement with a similar hole in the fuse base 10, and place in these holes a pin 38 which fits tightly enough so that it will only be moved downwardly into the hole in the fuse base and out of the hole in the disc 33 by the shock of firing. One of the members 34 is made 125 heavier than the other in order to ensure 130

the rotation of the disc 33 on its pivot when the fuse is rotated, and in order to ensure that the disc is retained in its rotated position, I provide a spring pressed catch 48

5 in the fuse base, that registers with the depression 39 (shown in dotted lines in Fig. 6) in the undersurface of the disc 33. A closure 40 is provided for the hole in the base in alinement with the hole 14. The 10 disc 33 is provided with a hole 41 immediately in front of the primer holder 35, this hole being brought into alinement with the hole 42 in the fuse base that leads to the powder chamber 43.

15 The operation of the modification of my invention just described is as follows, it being assumed that the parts are assembled as shown. The shock of firing forces the pin 38 out of the hole in the disc 33 and 20 into the hole in the fuse base 10, leaving the disc 33 free to rotate. When the shell, to which the fuse is attached, takes the rifling of the gun, it, and also the fuse, begin to rotate in the direction of the arrow, and 25 a consequent rotation of the disc 33 and attached parts due to the unbalance caused by the difference in weight of the members 34. The rotation of the disc 33 brings the primer 21 into the path of movement of 30 the firing pin, which is released at the proper instant by the timing gear (not shown) to explode the primer, the flames from the primer passing through the holes 41 and 42, which are at this instant in alinement, into 35 the powder charge in the chamber 43. As the disc 33 rotates to its extreme limit, as determined by the pin 37 and cut away portion 36, the spring pressed catch 48 moves upwardly into the depression 39, thus holding 40 the disc 33 and associated parts in the operated position.

Referring now to Fig. 7, which illustrates a modification similar to the modification illustrated in Figs. 5 and 6, 49 indicates the disc rotatably mounted in the recess 30, this disc being similar in construction to the disc 33, above described, except that it does not carry a primer holder and is not provided with a hole 41. Instead, the primer holder is identical with the primer holder illustrated in Figs. 2 and 3, and is therefore, designated by the reference character 15. The disc 49 is cut away at 50, which assists in overbalancing the same and thus assists 55 in the rotary movement and this cut away portion is brought into alinement with the hole 42 in the fuse base when the disc 49 is rotated to the operated position. The operation of this modification, being identical 60 with the operation of the modification illustrated in Figs. 5 and 6, need not be described.

While I have necessarily described the preferred embodiment of my invention somewhat in detail, it is to be understood that

I may vary the size, shape and arrangement of parts constituting my improved device, within wide limits without departing from the spirit of the invention.

My invention is further described and defined in the form of claims as follows:

1. In a time fuse, the combination of a base, a firing pin in said base movable in a right line and at right angles to the axis of the fuse in its flight, a primer lying in the path of movement of said firing pin, and a safety device interposed between said firing pin and primer, a second safety device retaining said first safety device in its normal position.

2. In a time fuse, the combination of a base, a firing pin in said base movable in a right line at right angles to the axis of the fuse in its flight, a primer lying in the path of movement of said firing pin, and a safety device interposed between said firing pin and primer and movable therefrom by centrifugal force, a second safety device retaining said first safety device in its normal position, said second safety device being operated by the shock of firing to release 85 said first safety device.

3. In a time fuse, the combination of a base, a firing pin in said base movable in a right line and at right angles to the axis 95 of the fuse in its flight, means normally tending to force said firing pin to its operated position, means for holding said firing pin in its normal position, a primer lying in the path of movement of said firing pin, 100 a safety device interposed between said firing pin and primer, a second safety device retaining said first safety device in its normal position, said safety devices being operated by the shock of firing and centrifugal 105 force respectively to clear the path of movement of the firing pin.

4. In a time fuse, the combination of a base, a firing pin in said base movable at right angles to the axis of the fuse in its 110 flight, means normally tending to force said firing pin to its operated position, means for holding said firing pin in its normal position, a primer lying in the path of movement of said firing pin, a safety device interposed between said firing pin and primer, 115 a second safety device retaining said first safety device in its normal position, said second safety device being operated by the shock of firing to release said first safety device, said first safety device being operated by centrifugal force to move out of the path of movement of said firing pin, and releasing means for said firing pin operating after the safety devices have operated. 120

5. In a time fuse, the combination of a base, a firing pin in said base, said firing pin being located in a passage extending diametrically of said base, a spring normally tending to force said firing pin to its 130

operated position, means for holding said firing pin in its normal position, a primer lying in the path of movement of said firing pin, a safety device interposed between said firing pin and primer and movable therefrom by centrifugal force, and releasing means for said firing pin operating after the safety devices have operated.

6. In a time fuse, the combination of a base, a firing pin in said base, said firing pin being located in a passage extending diametrically of said base, a spring normally tending to force said firing pin to its operated position, means for holding said firing pin in its normal position, a primer

lying in the path of movement of said firing pin, a safety device interposed between said firing pin and primer, a second safety device retaining said first safety device in its normal position, said second safety device being operated by the shock of firing to release said first safety device, said first safety device being operated by centrifugal force to move out of the path of movement of said firing pin, and releasing means for said firing pin operating after the safety devices have operated.

In testimony whereof, I have signed my name to this specification.

CHARLES H. PEARSON.
